UNITED STATES PATENT OFFICE

2,493,154

SHOE

Gus H. Mavrakis, Billings, Mont.

Application June 6, 1947, Serial No. 752,891

4 Claims. (Cl. 36—2.5)

1

This invention relates broadly to wearing apparel, and more particularly to a detachable and reversible upper for ladies' shoes.

The primary object of the present invention is to provide a shoe wherein the upper and bottom portions of the shoe are quickly and readily separable so that the upper may be reversed (turned inside out) or substituted by another upper of a different color or material.

Another important object of the present invention is to provide a shoe including a plurality of reversible uppers of various colors that are selectively engaged with the bottom or sole whereby the shoe may be used to conform to the costumes or the color of the costumes of the wearer.

A still further aim of the present invention is to provide a structure of the character heretofore described which is simple and practical in construction, strong and reliable in use, neat and attractive in appearance, relatively inexpensive to manufacture, which will effect a considerable savings in ladies' footwear and which is otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of a right shoe illustrating the invention;

Figure 2 is a top plan view of the bottom portion or shoe sole and with the inner sole of a left shoe removed therefrom;

Figure 3 is a flattened plan view of the shoe upper constituting the invention and shown detached from the sole;

Figure 4 is a transverse vertical sectional view taken substantially on the plane of section line 4—4 of Figure 1; and

Figure 5 is a perspective view of the case in which a plurality of folded uppers are conveniently kept, and with parts of the case broken away and shown in section.

Referring now to the drawings in detail, wherein for the purpose of illustration the numeral 10 represents the bottom portion or sole of a shoe generally comprising an outer sole 12, a heel 14, an inner sole 16 extending the full length of the shoe, and a pair of auxiliary inner paddings 18 and 19 interposed between the forward portion of the inner sole and the outer sole and constituting a platform. This type sole and heel, previously described, is conventional and constitutes no part

2

of the invention, hereinafter to be described, and capable of use with other style soles and heels.

Suitably secured by stitchings, glue or the like between the inner paddings 18 and 19 is one portion of a flexible supporting tape 20 on which is carried one-half or mating section 22 of a conventional slide fastener having a slide 24 mounted thereon.

Said mating section extends from adjacent the shank on one side of the sole around the toe and rearwardly to a similar point on the other side of the sole.

The numeral 28 represents the upper portion of the shoe generally, comprising a substantially U-shaped body formed of two correspondingly shaped plies 29 and 30, which are stitched or otherwise secured together at their edges and which are of distinct color and/or flexible material such as leather, cloth or the like, and which with the slide fastener constitutes the invention.

The outer marginal edges of these materials 29, 30 are tapered at their rear portions or adjacent their ends toward the inner marginal edges thereof, as seen at 32, to provide extensions of reduced widths forming straps 34 and 36. The strap 34 has a plurality of spaced openings 38 that are selectively engaged by the pivotal arm 40 of a buckle 42 carried by the free end of the other strap 36 for adjustment of the straps 34 and 36 about a user's heel.

The forward portion of the upper 28 is notched or cut out, as at 44, to provide an air space or toe opening.

Secured by stitching or the like about the forward and outer marginal edges of the materials 29 and 30 and extending to the tapered portions 32, is a supporting tape 46 supporting the complementary mating section or portion 48 of the slide fastener engageable with fastener section 22 by operation of slide 24.

In practical use of the invention, a plurality of reversible uppers 28 are provided of various colors, materials and designs on each face thereof, and extra uppers 28 may be neatly folded and carried in a case 52 of preferably leather material. The open end of this case is conveniently opened or closed by a slide fastener and slide 54, so that the case may be opened for accessibility to the auxiliary uppers for selectively engaging the same with the pair of shoe soles or bottoms 10. These uppers are so designed as to fit either the sole 10 for the left foot or the right foot. Accordingly, the slide fastener section 48 of each upper 28 will engage the fastener section 22 of the right sole 10 with one side of the upper outer-

most and the fastener section 22 of the left sole 10 with the other side of the upper outermost.

Accordingly, it will be apparent that any number of pairs of uppers 28 may be utilized with a single pair of shoe soles 10 thus enabling the wearer to be provided with shoes which match in color and texture with a dress, suit or other garment being worn, without the necessitating of purchasing a separate pair of shoes for each ensemble. Likewise, it will be readily apparent that the extra uppers 28 may be conveniently carried so that for the purpose of travelling, or at other times where a change of wearing apparel is to be made away from home, it will be unnecessary to carry extra pair or pairs of shoes. Likewise, each pair of uppers 28 by being of different colors and/or materials on different sides thereof are capable of use with two distinct ensembles. The mating sections of the slide fastener secured to the shoe soles 10 and uppers 28 are engaged and disengaged by the slide 24 in a conventional manner for completely detaching or for attaching the uppers on both the inner and outer sides of the soles and uppers from the toe to adjacent the shank or inner side of the heel, as clearly illustrated in Figures 1 and 2. Likewise, the slide fastener mating sections and the slide 24 may be made ornamental to enhance the appearance of the upper 28 being worn, as by being of a gold or silver color to blend attractively with the different colored uppers and to replace ornamental studs or similar items conventionally applied to ladies' shoes.

It is to be understood, however, that even though there is herein shown and described a preferred embodiment of the invention, the same is susceptible to certain changes fully comprehended by the spirit of the invention as herein described and within the scope of the appended claims.

I claim as my invention:

1. A pair of shoes comprising a pair of shoe soles, a pair of shoe uppers, and fastening means for detachably connecting each shoe upper to one of the shoe soles from a point adjacent the heel, on one side of the sole, around the toe and to a corresponding position on the other side of the sole, for disposition thereabove, said shoe uppers having opposite finished faces of different colors and/or materials, said fastening means being constructed and arranged to permit each upper to be connected to one shoe sole with one finished face of the upper externally disposed and to the other sole with its other finished face disposed externally, said fastening means comprising pairs of slide fasteners having complementary sections fixed to the shoe soles and complementary sections fixed to the shoe uppers and extending around the toes and rearwardly on both sides of the shoe soles and uppers to adjacent the shoe shanks, and a slide carried by the mating fastener section of each shoe sole and detachably connected to the fastener section of either shoe upper for detachably and reversibly connecting the shoe uppers to the shoe soles.

2. A pair of shoes comprising a pair of shoe soles, a pair of shoe uppers, and fastening means for detachably connecting each shoe upper to one of the shoe soles from a point adjacent the heel, on one side of the sole, around the toe and to a corresponding position on the other side of the sole, for disposition thereabove, said shoe uppers having opposite finished faces of different colors and/or materials, said fastening means being constructed and arranged to permit each upper to be connected to one shoe sole with one finished face of the upper externally disposed and to the other sole with its other finished face disposed externally, said fastening means comprising pairs of slide fasteners having complementary sections connected to the shoe soles and complementary sections connected to the shoe uppers, said slide fasteners extending around the toes of the shoe soles and uppers and rearwardly on both sides to points adjacent the heels, and a slide carried by the mating section of each shoe sole for detachably engaging either slide fastener section of the shoe uppers for reversibly mounting the shoe uppers on the shoe soles, each shoe upper being provided with a cut-out toe portion combining with a portion of the fastener section connected thereto to form a toe opening therein.
3. In combination with a pair of shoe soles, a pair of shoe uppers having opposite finished faces of different colors and/or materials, and slide fastener means for detachably and reversibly connecting the shoe uppers to the shoe soles and including complementary slide fastener sections connected to the shoe soles and complementary fastener sections connected to the shoe uppers, a slide nondetachably carried by each fastener section of the shoe soles for detachably engaging the slide fastener section of either shoe upper for mounting the shoe uppers on the shoe soles with either finished face of the shoe uppers outermost.
4. A shoe comprising a sole having slide fastener means on its upper surface, the slide member of the slide fastener means being permanently carried by the sole member, an upper having a cooperating slide means on its lower surface for engagement with the slide means on the sole, and said upper being finished on both sides thereof whereby the upper may be reversed for use with the matching sole with which it is associated.
